DESIGN FOR A SHOE SOLE

Conrad Ferrettie and George W. Blair, Mishawaka, Ind., assignors to Mishawaka Rubber and Woolen Manufacturing Company, Mishawaka, Ind., a corporation of Indiana

Application June 6, 1941, Serial No. 101,326

Term of patent 14 years

To all whom it may concern:

Be it known that we, Conrad Ferrettie and George W. Blair, citizens of the United States, residing at Mishawaka, in the county of St. Joseph, State of Indiana, have invented a new, original, and ornamental Design for Shoe Soles, of which the following is a specification, reference being had to the accompanying drawing, forming part thereof.

Fig. 1 is a bottom plan view of a shoe sole, showing my new design;

Fig. 2 is a fragmentary longitudinal sectional view on line 2—2 of Fig. 1; and

Fig. 3 is a cross-sectional view on the line 3—3 of Fig. 1.

We claim:

The ornamental design for a shoe sole, substantially as shown.

CONRAD FERRETTIE.
GEORGE W. BLAIR.
